HEATING UNIT FOR BITUMINOUS MATERIALS

James A. Brock and Doyle L. Spears, Chattanooga, Tenn.; said Spears assignor to Cobble Brothers Machinery Company, Inc., Chattanooga, Tenn., a corporation of Tennessee

Application May 9, 1955, Serial No. 507,016

4 Claims. (Cl. 126—343.5)

This invention relates to a portable heating unit for bituminous materials and more particularly to a self-contained portable heating tank for bituminous materials.

Bituminous materials, such as asphalt, are customarily transported in solid form in railroad tank cars. In the bottom of these tank cars are steam coils to which steam is introduced from a power plant when the tank car arrives at its destination. The heat from the steam coils converts the solid bituminous material into liquid so that it may be pumped from the tank car into a tank truck or into a stationary receptacle. In mixing the bituminous material with gravel to form paving material, the bituminous material must be at a temperature of about 350° F. in order that it may bond properly with the gravel. When the liquid bituminous material leaves the railroad tank car, it is at approximately 200° F. Consequently, it must again be heated until the temperature is elevated to the required 350° F.

Various apparatuses and methods have been employed to prepare the bituminous materials for paving operations. Most of these apparatuses have employed two heating systems, one generally a boiler for providing steam to the steam coils in a railroad tank car and a second heating unit for elevating the temperature of the liquid material to 350° F., such as a direct-fired gas or oil burner, or a jacketed oil or gas burner which supplies heat to a heat transfer medium, such as oil, which is in turn circulated to heat the bituminous material.

Another disadvantage of present conventional heating and mixing plants for paving material is the fact that in highway construction such plants have to be frequently moved to keep pace with the progress of the highway construction. The plants have to be dismantled, transported and reassembled at a new site close to the current construction operation. Because of the size of these plants, their transportation requires approximately a thousand man-hours, not only because of the dismantling, moving, and reassembling, but also because the heat generating plants must be allowed to cool before dismantling, and also must be fired up again after reassembling. Even after the heat generating plant is refired, it requires considerable time for the thousands of gallons of bituminous material to be heated to a temperature of 350° F.

It is therefore an object of this invention to overcome the disadvantages enumerated and to provide a simple compact heating unit which will provide an economical method of heating the bituminous materials to the desired temperature as well as providing steam power for other plant operations.

Another object of this invention is to provide a large heating tank containing a fire tube boiler for generation of steam and which employs the waste heat of the flue gases for heating the bituminous materials.

It is a further object of this invention to provide a self-contained portable unit for heating bituminous material as well as generating steam power for other plant operations.

2

Further objects and advantages of the invention will be apparent from the following description taken in conjunction with the drawing, wherein:

Fig. 1 is a side elevation with the tank, canopy, and rear platform in section along lines 1—1 of Fig. 3 and illustrating a preferred embodiment of the invention;

Fig. 2 is a section taken along the lines 2—2 of Fig. 1;

Fig. 3 is a rear end elevation of the apparatus disclosed in Fig. 1, with portions of the rear axle and supporting beams broken away; and

Fig. 4 is a sectional view along the line 1—1 of Fig. 3.

Briefly stated the invention comprises a large portable tank for receiving bituminous materials. Horizontally disposed within the tank is a fire tube boiler, the heat receiving end of said boiler opening through the rear end of the tank to communicate with a combustion chamber which is located outside the tank. The combustion chamber may be fired by any type fuel burner, such as oil or gas. At the forward end of the boiler within the tank is a header for receiving the exhaust gases from the boiler tubes and distributing said gases to a plurality of stack flues. These stack flues extend subjacent to and substantially horizontally along the bottom of the tank and discharge into an exhaust header just outside the rear end of the tank. It is important that these stack flues be located near the bottom of the tank in order that they may immediately begin heating the initial portion of the bituminous material which is poured into the tank. As the tank is filled, the heated portions of the bituminous material near the bottom will rise to the top creating convection currents causing a uniform temperature throughout the material in the tank. Because the stack flues are beneath the boiler, an induced draft fan communicating with the outside exhaust header is necessary to create a draft in the combustion chamber, boiler tubes, and stack flues. The steam generated in the boiler is released through a steam dome and exhaust valves outside the tank. There is little heat transfer between the outside of the boiler and the bituminous material as compared with the heat transfer from the stack flues. Steam coils may be included within the tank to accelerate the heating of the bituminous material by utilizing a portion of the steam generated by the boiler. However, most of the steam from the boiler is used for liquefying bituminous material in railroad tank cars and for other plant operations, such as providing steam to jacketed conduits for transporting the hot bituminous material in liquid condition and supplying steam to steam-atomizing burners used for drying gravel before it is mixed with the bituminous material. In this manner the invention contemplates satisfying the heating and power requirements for the production of paving material from a single heat generating unit.

Referring now to the drawings in detail, a large tank 10 for containing liquid bituminous material has an inlet 11 near the top and an outlet 12 near the bottom of the tank in the rear wall 13. Extending through the rear wall 13 and horizontally disposed within the tank 10 is a fire tube boiler 14 containing boiler tubes 15. Extending from the top of the boiler 14 and upward through the top of the tank 10 is a steam dome 16 provided with steam outlets 17. A steam header 18 is mounted on the rear wall 13, having inlet 19 and outlets 20. Steam is fed from one of the dome outlets 17 through conduit 21 to inlet 19. From the header outlets 20, connections are made to supply steam for power and plant operations to be later described.

At the forward end of the boiler 14, an exhaust header 22 supported from the bottom of the tank 10 by saddle bracket 23 collects the exhaust gases from the boiler tubes 15 and distributes the gases to stack flues 24, communicating with the bottom portion of the header 22.

and extending horizontally back beneath the fire tube boiler 14 and near the bottom of the tank 10, until the flues communicate with a stack flue header 25 mounted on the outside of the rear wall 13. An induced draft fan 26 is connected to stack flue header 25 to draw the gases from the stack flues and discharge the gases through exhaust port 28.

A cylindrical combustion chamber 29 having refractory-lined inner walls is mounted on a frame 30 supported on rear platform 27 to communicate with fire tube boiler 14 through the rear wall 13. A heat generator such as oil burner 31 communicating with the rear end of combustion chamber 29 provides a combustible mixture of air and oil to the combustion chamber, where the mixture is ignited and then passes through the boiler tubes 15 to generate steam in the boiler 14.

To receive the return condensate from an external steam power operation to which steam has been supplied from header 18, a pair of saddle tanks 32 and 33 are mounted along opposite sides of the tank 10. Inlets 34 and 35 are located in the ends of and near the tops of each saddle tank respectively, through which condensate is received. A feed water pump 36 is mounted in saddle tank 33 and pumps water from saddle tank 33 through conduit 37 to the boiler 14. The saddle tanks 32 and 33 are connected by conduit 38 so that water in both tanks will be at the same level. The location of the saddle tanks against such a large exposed surface of the tank 10 allows the water within the saddle tanks to absorb a large quantity of heat radiating from the tank 10 which would otherwise be wasted. In this manner, the feed water is pre-heated to increase the efficiency of the boiler 14.

As a supplemental source of heat within the tank, steam coils 40 may be arranged horizontally in the bottom of the tank 10 below the stack flues 24 and supplied with steam through conduit 41 from one of the steam header outlets 20. The condensate from the coils 40 flows through conduit 42 to saddle tank 32.

To prevent an excessive amount of bituminous material from falling upon the steam coils 40 and to allow the coils to heat small quantities of material at a time, a cover plate 43 having apertures 44 is spaced above the coils 40 and below the stack flues 24. The apertures 44 permit small streams of bituminous material to flow around the coils 40, where the material may be further heated and circulated into the upper portion of the tank 10 or may be withdrawn through outlet 12.

To make the entire heating unit portable, it is mounted on a trailer comprising supporting beams 45 and 46 which extend longitudinally beneath the rear platform 27 and the tank 10, the beams terminating at their forward ends in a tongue 47 adapted to be connected to a prime mover 48. The rear portions of the beams are supported by wheels 49. A control panel 50, containing controls and gauges for regulating the low water, temperature, and pressure of the boiler and for regulating the burner 31 and induced draft fan 26, is located in any convenient position and is shown in Figs. 1 and 3 mounted alongside the combustion chamber 29. A canopy 51 may extend out from the rear wall 13 to protect the instruments, the machinery and also the operator from inclement weather. Water glass 52 is mounted on rear wall 13 to determine the water level in the boiler 14.

The tank 10 may also be provided with a fuel reservoir 53 located in the forward end of the tank 10 to provide fuel to the burner 31 through conduit 54. The reservoir is provided with fuel inlet 55.

The operation of the heating unit is as follows:

The portable unit may be moved to a position adjacent a railroad siding in order that its boiler may generate sufficient steam to melt the bituminous material in a railroad tank car standing on the siding, and to receive the liquid bituminous material in the tank 10, where the material may be further heated by the stack flues 24. When

the liquid bituminous material is sufficiently heated, preferably to about 350° F., the liquid is drained from outlet 12 into tank trucks for conveyance to a road paving mixing plant or into tank trucks having distributors for directly spraying the liquid material upon road surfaces.

An alternative and important use of the unit is obtained when it is stationed adjacent a road paving mixing plant where the tank 10 may receive liquid bituminous material from tank trucks or from steam jacketed supply conduits. The liquid bituminous material is heated to higher temperatures by the stack flues 24, and then conveyed to the mixing plant where it is bonded with gravel to form a paving material. The boiler 14 provides steam for the power plant operations of the mixing plant, and primarily to supply steam to the steam-atomizing burner which pre-dries the gravel.

Even though the boiler 14 is located entirely within the tank 10, comparatively little heat is transferred from the boiler to the bituminous material within the tank. The bituminous material depends for its heat almost entirely upon the stack flues 24, which carry the exhaust gases from the boiler tubes 15 back through the tank 10 subjacent to the boiler 14 and near the bottom of the tank to the stack flue header 25, where the gases are discharged through exhaust port 28. The steam generated in the boiler 14 is used almost exclusively for operations external to the heating unit.

In cases where a more rapid rate of heating or a higher temperature is desired within the tank 10, the steam coils 40 located in the bottom of the tank may provide this additional heat from steam generated in the boiler 14 and tapped from the steam header 18 through conduit 21.

It is important that the stack flues 24 be located beneath the boiler and near the bottom of the tank 10, in order that the flues may begin to heat the initial portion of the liquid bituminous material as it accumulates in the bottom of the tank 10. Furthermore, as the liquid near the bottom of the tank becomes heated, it rises, setting up liquid convection currents, thus creating a uniform liquid temperature throughout the tank.

Because of the large capacity, in the order of 20,000 gallons, and the portability of the unit, it is designed to assume semi-permanent positions in road building operations. The unit may remain in one location for one or several days, being able to supply liquid bituminous material at 350° F. for several hours before being refilled. When a road building operation has proceeded beyond the range of convenient supply, then the unit may be attached to a prime mover and conveyed to a new site easily accessible to the road building operations.

Furthermore, the large capacity of the tank provides an excellent insulation of bituminous material surrounding the boiler 14. It has been found that when the unit is idle during an overnight period, the drop in temperature of the material in the bottom of the tank is only about 100° F. Consequently, about thirty minutes after the boiler is refired, the unit is capable of discharging bituminous material at approximately 350° F. From a cold start, the unit is ready to discharge bituminous material at that temperature within one hour.

Although the number and size of the boiler tubes 15 and the stack flues 24 are not material to this invention so long as the total cross sectional area of the stack tubes 24 is equal to or exceeds the total cross sectional area of the fire tubes 15, a satisfactory arrangement has been found in providing the boiler with 53 2" O. D. boiler tubes and 23 3" O. D. stack flues.

The use of a compact portable heating unit for bituminous materials such as the one described, which utilizes one source of energy to provide high grade steam power for external power plant operations, to provide steam for other uses, and also to provide a heating supply to raise the temperature of liquid bituminous material contained within the tank of the unit, results in a savings of approxi-

mately 60% of the fuel consumption by conventional methods heretofore used employing separate energy sources for steam power and for heating the bituminous material. Furthermore, by employing such a compact and portable heating unit, approximately a thousand man-hours are conserved by the elimination of a single dismantling and reassembling operation previously incurred in moving pavement mixing plants and machinery from one site to another in order to keep pace with the progress of the road paving and construction.

It will be apparent to those skilled in the art that various changes may be made in the invention, without departing from the spirit and scope thereof, and therefore the invention is not limited by that which is shown in the drawings and described in the specification, but only as indicated in the appended claims.

In place of heating water to generate steam in the boiler 14, a heat-transfer medium such as mineral oil can be used in the boiler and circulated through tank cars and the coils 40 in the bottom of the tank. Furthermore, applicants' apparatus can be used to heat other fluids, such as water, in the tank 10.

What is claimed is:

1. A heating apparatus comprising a tank containing material to be heated, a fire tube boiler containing a fluid to be heated extending substantially parallel to the bottom of said tank, the heat receiving end of said boiler extending through the rear end of said tank, a combustion chamber outside the tank and communicating with the receiving end of the boiler and means for firing said combustion chamber, a gas collecting header communicating with the gas discharge end of the boiler, a plurality of fire tubes within said boiler communicating said combustion cham-

ber with said header, a plurality of flues extending along the greater portion of the length of and within said tank, said flues being disposed outside of and subjacent to the boiler and substantially parallel to and near the bottom of said tank, said flues communicating with said header and terminating outside the rear end of the tank, and means for exhausting gas from said flues.

2. A heating apparatus comprising a tank containing material to be heated, a boiler containing a heat-exchange fluid within the tank, a fuel burner and a combustion chamber outside the tank, a plurality of fire tubes within the boiler and communicating at their one ends with said combustion chamber, an exhaust header with which the other ends of the fire tubes communicate, a plurality of return flues outside of and below the boiler and within the tank near the bottom thereof communicating at their one ends with the exhaust header and a stack flue header with which said return flues communicate at their other ends.

3. The invention according to claim 2 in which the boiler, fuel burner, combustion chamber, fire tubes and return flues are horizontally disposed.

4. The invention according to claim 2 in which the exhaust header is outside the boiler but within the tank and the stack flue header is outside the tank.
